BOLSTER

Herbert G. Beede, Pawtucket, R. I.

Application May 23, 1938, Serial No. 209,470

12 Claims. (Cl. 308—169)

My invention relates to means for non-rotatably securing the lower end of bolster means to the lower end of a bolster case in a spindle having a rotatable spindle blade, a bolster case adapted to be rigidly secured to a machine frame and floating bolster means interposed between said case and rotatable spindle blade.

An object of my invention is to provide a novel type of means for this purpose located at the lower end of a bolster and bolster case to secure the bolster against rotary creeping within the case in use.

My invention is adapted for use in any type of a spindle whether it employ a single bolster or a plurality of nested bolsters as shown in the joint pending application of myself and Frederic N. Beede for Spindles and mountings or journals therefor, Ser. No. 114,997, filed Dec. 9, 1936. It is particularly adapted for use where it is not possible or not desirable to provide a bolster lock near the upper end thereof, as in the devices shown in said application it is desirable to keep the bolster lock at the lower end of the bolster below the level of the oil within the case to positively maintain an unbroken surface on the outer surface of a bolster so that oil may be evenly fed upwardly between the outer surface of the bolster means and the bolster case or between an inner bolster and an outer bolster.

A further object of my invention is to provide improvements in the specific means usually employed for securing the lower end of the bolster means against relative rotation within the bolster case. Former types of means for this purpose have usually comprised pin locks. It has been found in practice, however, that any type of pin lock distorts the vibration at the foot of the bolster, particularly, at high speeds and heavy loads.

These and such other objects of my invention as may hereinafter appear will be best understood from a description of the accompanying drawings, which illustrate various embodiments of my invention.

In the drawings, Fig. 1 is a vertical sectional view taken through the center portion of a rotatable spindle and employing my invention for non-rotatably securing the lower end of an outer bolster against rotation within the bolster case, the spindle being shown in elevation.

Fig. 2 is a view similar to Fig. 1 with the spindle, step bearing and whirl removed showing the bolster means being inserted within the bolster case to permit the interengaging means on the lower end of the outer bolster and case base plug to interlock during such insertion.

Fig. 3 is a cross sectional view taken along the line 3—3 of Fig. 1.

Fig. 4 is a side elevation of the case base plug constructed in accordance with my invention employed in the embodiment shown in Figs. 1—3.

Fig. 5 is a vertical sectional view similar to Fig. 1 of an embodiment of my invention employing a single bolster.

Fig. 6 is a cross sectional view taken along the line 6—6 of Fig. 5.

Fig. 7 is a vertical sectional view illustrating an embodiment of my invention for non-rotatably securing the lower end of an inner bolster against rotation within a bolster case.

Fig. 8 is a cross sectional view taken along the line 8—8 of Fig. 7.

Fig. 9 is a side elevation of the specific form of base plug employed in this embodiment.

Fig. 10 is a vertical sectional view taken through the lower end of a spindle showing an alternative embodiment of my invention for non-rotatably securing the lower end of an inner bolster within the lower end of a bolster case.

Fig. 11 is a cross sectional view taken along the line 11—11 of Fig. 10.

Fig. 12 is a side elevation of a base plug adapted for use in the embodiment of my invention shown in Figs. 10 and 11.

In the drawings, wherein like characters of reference generally indicate like parts throughout, 20 generally indicates a bolster case for receiving a rotatable spindle blade 22 therein. The bolster case 20 is adapted to be secured to the frame or other portion of the machine by the circumferential projection 24 to hold the bolster case 20 in proper position on the machine. Textile spindles of this type are also provided with floating tubular bolster means 26 mounted within said case 20 intermediate said case and spindle blade 22. I have shown in Figs. 5—8 my invention adapted for a standard type of spindle employing a single bolster 26 but my invention is peculiarly adapted for use with spindles employing a plurality of nested bolsters such as the inner bolster 26a and the outer bolster 26b as shown in the other figures.

The bolster means 26 whether it comprise a single bolster or plurality of nested bolsters 26a and 26b extends substantially to the top of the bolster case 20 and is usually loosely fitted in the bolster case so as to have a floating action therein. The lower end of the spindle blade 22 usually terminates in the pointed tip 28 and extends downwardly within the step bearing bushing 30 mounted within said bolster means having

a central hole 32 for loosely receiving the lower end of said spindle blade 22 and a step 34 mounted within said bushing hole 32 for mounting the lower tip 23 of the spindle blade 22 thereon. The step 34 as shown is mounted in the lower end of said bushing by means of the pin 36 projecting through a diametric hole 38 in the step 34 and diametric holes in the lower end of the step bushing 30.

As stated hitherto, pin locks for non-rotatably securing the lower end of the bolster within the bolster case as employed in the prior art have hindered free vibration at the foot of the spindle particularly at high speeds and heavy loads and have tended to work loose in practice and it is to an alternative type of means for this purpose that my invention relates as will be more particularly described.

A suitable type of bearing means 40 such as a ball bearing shown is usually provided near the upper end of the spindle for pivotally securing the spindle within the bolster to provide a suitable axis of oscillation therefor, a ball bearing being preferable as it tends to provide a more perfect axis of oscillation. The spindle blade 22 is usually keyed or fastened to the inner race of the ball bearing 40 which is driven by the usual whirl 42 which receives and drives the bobbin by the key 44 shown to receive a suitable channel in the interior of the bobbin for this purpose. The whirl 42 preferably extends around the bearing 40 and projects substantially downwardly to the projection 24 for retaining the bolster case on the machine frame.

As stated hitherto, my invention particularly relates to cooperating interengaging means on the lower end of the bolster means 26 and lower end of said case 20 for positively relatively non-rotatably securing said bolster means within the bolster case and in my preferred embodiment said means comprise a plurality of circumferentially extending radially spaced fingers 46 projecting axially upwardly within the outer portion of the lower end of said case and a plurality of complementary circumferentially extending radially spaced slots 48 in the lower end of said bolster means of greater width than said fingers for loosely receiving said fingers 46 therein to provide the necessary clearance for free vibration at the foot of the spindle, particularly desirable at high speeds and heavy loads heretofore referred to.

In my preferred embodiment, the fingers 46 project axially upwardly from the outer edge of a base plug 50 for forming the closed lower end of the case 20 as is usual in the art and the plurality of complementary circumferentially extending radially spaced slots 48 may be provided in the lower end of the single bolster 26 as shown in Figs. 5-8, or in the lower end of an outer bolster, one species therefor being shown in Figs. 7-9 and another species therefor being shown in Figs. 10-12. The standard type of base plug has a solid cylindrical lower end provided with the annular circumferential groove 52 at the lower extremity thereof so that when said plug 50 is inserted within the lower end of the case, solder 54 may be inserted within said groove 52 as usual for sealing the plug 50 within the lower end of the case 20 to close the lower end of the case. The base plug may be provided with the central circular ledge 56 for receiving the lower end of the step 34 and step bushing 30 thereon so as to provide an oil

circulating annular channel 58 between said central ledge and fingers 46.

The slots 48 in my preferred embodiment shown are preferably of a greater length than said fingers 46 to provide radial oil circulating holes 58 between the upper ends of said fingers 46 and upper ends of said slots 48. Where the base plug 50 is employed for sealing the lower end of the case 20, it is obvious that the fingers 46 may project upwardly from the outer edge of said base plug as shown in Figs. 1-9.

I have shown in Figs. 7-10 one embodiment of means for securing the inner bolster against relative rotation within the bolster case 20 (the inner bolster 26a being suitably secured against relative rotative movement to the outer bolster 26b by a key 60 projecting radially from one of said bolsters within a spline 62 therefor in the other of said bolsters) and an alternative type 20 of means for securing the inner bolster 26a within the case 20 against relative rotation therein in Figs. 10-12.

As shown in Figs. 7-9, the fingers 46 are continued a substantial distance radially inwardly thereof so that they may project within the slots 48a in the inner bolster 26a and also the slots 48b in the outer bolster 26b. Alternatively the fingers 46 may be radially inset from the periphery of the plug as shown in Figs. 10-12 thereby forming an annular shoulder 63 on said plug 50 exterior of said fingers 46 so that the lower end of the outer bolster 26b may rest on said annular shoulder 63.

As stated hitherto, my improved type of means hitherto described is particularly desirable where a plurality of bolsters are employed so that the oil may be evenly fed axially upwardly of the outer surface of the outer or inner bolster as in the constructions shown in the aforesaid application. Thus, in the embodiment shown in Fig. 1, constructed in accordance with said invention, oil is circulated from the clearance 68 between the hole 32 in the step bearing bushing 30 and the lower end of the spindle 22, out through the diametric holes 70 in said step bearing bushing 30, underneath the lower end of the inner bolster radially outwards through the oil circulating channel 56, upwards between the inner bolster and fingers 46, then radially outwards through the radial oil circulating holes 58 formed between the upper end of the fingers 46 and upper end of the channels 48 in the outer bolster and axially upwardly of the outer surface of the outer bolster 26b. In similar fashion does the oil circulate in the embodiments of my invention shown in Figs. 7 and 10, the oil passing radially outwardly between the inner and outer bolsters through the radial holes 72 provided for this purpose in the outer bolster. In all instances the oil is fed over the upper surface of the outer and/or inner bolster to be brought down over the bearing 40 to lubricate it to again flow back into the clearance 68 between the hole 32 in the step bearing bushing 30 and the lower end of the spindle 22 thereby continuously recirculating in accordance with the principles of said invention.

It is apparent therefore that I have provided a novel type of means for non-rotatably securing the lower end of bolster means to the lower end of a bolster case with the advantages described above.

It is understood that my invention is not limited to the specific embodiments shown and that various deviations may be made therefrom with-

out departing from the spirit and scope of the appended claims.

What I claim is:

1. Means for non-rotatably securing the lower end of bolster means to the lower end of a bolster case in a spindle having a rotatable spindle blade, a bolster case adapted to be rigidly secured to a machine frame having a base plug contained within the lower end thereof, a floating outer bolster within the bolster case, and a floating inner bolster within said outer bolster, comprising a plurality of circumferentially extending radially spaced fingers projecting axially upwardly from the outer portion of said base plug, and a plurality of complementary circumferentially extending radially spaced slots in the lower end of a outer bolster of greater width than said fingers for loosely receiving said fingers therein.

2. Means for non-rotatably securing the lower end of bolster means to the lower end of a bolster case in a spindle having a rotatable spindle blade, a bolster case adapted to be rigidly secured to a machine frame, a floating outer bolster within the bolster case, and a floating inner bolster within said outer bolster, comprising a plurality of circumferentially extending radially spaced fingers extending axially upwardly within the outer portion of the lower end of the bolster case, and a plurality of complementary circumferentially extending radially spaced slots in the lower end of said outer bolster of greater width than said fingers for loosely receiving said fingers therein.

3. Means for non-rotatably securing the lower end of bolster means to the lower end of a bolster case in a spindle having a rotatable spindle blade, a bolster case adapted to be rigidly secured to a machine frame having a base plug contained within the lower end thereof, a floating outer bolster within the bolster case, and a floating inner bolster within said outer bolster, comprising a plurality of circumferentially extending radially spaced fingers projecting axially upwardly from the outer portion of said base plug, and a plurality of complementary circumferentially extending radially spaced slots in the lower end of said inner bolster of greater width than said fingers for loosely receiving said fingers therein.

4. Means for non-rotatably securing the lower end of bolster means to the lower end of a bolster case in a spindle having a rotatable spindle blade, a bolster case adapted to be rigidly secured to a machine frame, a floating outer bolster within the bolster case, and a floating inner bolster within said outer bolster, comprising a plurality of circumferentially extending radially spaced fingers extending axially upwardly within the outer portion of the lower end of the bolster case, and a plurality of complementary circumferentially extending radially spaced slots in the lower end of said inner bolster of greater width than said fingers for loosely receiving said fingers therein.

5. Means for non-rotatably securing the lower end of bolster means to the lower end of a bolster case in a spindle having a rotatable spindle blade, a bolster case adapted to be rigidly secured to a machine frame having a base plug contained within the lower end thereof, a floating outer bolster within the bolster case, and a floating inner bolster within said outer bolster, comprising a plurality of circumferentially extending radially spaced fingers projecting axially upwardly from the outer portion of said base plug, radially inset from the periphery thereof forming

an annular shoulder on said plug exterior thereof, and a plurality of complementary circumferentially extending radially spaced slots in the lower end of said inner bolster of greater width than said fingers for loosely receiving said fingers therein, the lower end of said outer bolster resting on said annular shoulder of said plug.

6. Means for non-rotatably securing the lower end of bolster means to the lower end of a bolster case in a spindle having a rotatable spindle blade, a bolster case adapted to be rigidly secured to a machine frame, a floating outer bolster within the bolster case, and a floating inner bolster within said outer bolster, comprising a plurality of circumferentially extending radially spaced fingers extending axially upwardly within the outer portion of the lower end of the bolster case, radially inset from the periphery thereof forming an annular shoulder exterior thereof, and a plurality of complementary circumferentially extending radially spaced slots in the lower end of said inner bolster of greater width than said fingers for loosely receiving said fingers therein, the lower end of said outer bolster resting on said annular shoulder.

7. Means for non-rotatably securing the lower end of bolster means to the lower end of a bolster case in a spindle having a rotatable spindle blade, a bolster case adapted to be rigidly secured to a machine frame having a base plug contained within the lower end thereof, a floating outer bolster within the bolster case, and a floating inner bolster within said outer bolster, comprising a plurality of circumferentially extending radially spaced fingers projecting axially upwardly from the outer edge of said base plug, and extending for a substantial distance radially inwardly thereof, and a plurality of complementary circumferentially extending radially spaced slots in the lower end of both of said bolsters of greater width than said fingers for loosely receiving said fingers therein.

8. Means for non-rotatably securing the lower end of bolster means to the lower end of a bolster case in a spindle having a rotatable spindle blade, a bolster case adapted to be rigidly secured to a machine frame, a floating outer bolster within the bolster case, and a floating inner bolster within said outer bolster, comprising a plurality of circumferentially extending radially spaced fingers extending axially upwardly within the outer portion of the lower end of the bolster case, and extending for a substantial distance radially inwardly thereof, and a plurality of complementary circumferentially extending radially spaced slots in the lower end of both of said bolsters of greater width than said fingers for loosely receiving said fingers therein.

9. A base plug adapted to be contained within the lower end of a tubular bolster case for a rotatable spindle comprising a solid member of the configuration of the lower end of the bolster case having a plurality of axially extending radially spaced fingers projecting upwardly from the outer edge thereof, and radially inset from the periphery thereof forming an annular shoulder on said plug exterior thereof.

10. A base plug adapted to be contained within the lower end of a tubular bolster case for a rotatable spindle comprising a solid member of the configuration of the lower end of the bolster case having a plurality of axially extending radially spaced fingers projecting upwardly from the outer edge thereof, and extending for a substantial distance radially inwardly thereof.

11. Means for non-rotatably securing the lower end of bolster means to the lower end of a bolster case in a spindle having a rotatable spindle blade, a bolster case adapted to be rigidly secured to a machine frame having a base plug contained within the lower end thereof, a floating outer bolster within the bolster case, and a floating inner bolster within said outer bolster, comprising a plurality of circumferentially extending radially spaced fingers projecting axially upwardly from the outer portion of said base plug, and a plurality of complementary circumferentially extending radially spaced slots in the lower end of at least one of said bolsters of greater width than said fingers for loosely receiving said fingers therein.

12. Means for non-rotatably securing the lower

end of bolster means to the lower end of a bolster case in a spindle having a rotatable spindle blade, a bolster case adapted to be rigidly secured to a machine frame, a floating outer bolster within the bolster case, and a floating inner bolster within said outer bolster, comprising a plurality of circumferentially extending radially spaced fingers extending axially upwardly within the outer portion of the lower end of the bolster case, and a plurality of complementary circumferentially extending radially spaced slots in the lower end of at least one of said bolsters of greater width than said fingers for loosely receiving said fingers therein.

13. HERBERT G. BEEDE.
